US0D1031643S

(12) **United States Design Patent** (10) Patent No.: **US D1,031,643 S**
(45) Date of Patent: ** Jun. 18, 2024

(54) **CHARGING CASE FOR EARPHONES**

(71) Applicant: **LINSATION INTELLIGENT TECHNOLOGY (SHENZHEN) LIMITED**, Shenzhen (CN)

(72) Inventor: **Tao Zhong**, Shenzhen (CN)

(73) Assignee: **LINSATION INTELLIGENT TECHNOLOGY (SHENZHEN) LIMITED**, Shenzhen (CN)

(**) Term: **15 Years**

(21) Appl. No.: **29/790,569**

(22) Filed: **Dec. 3, 2021**

(51) LOC (14) Cl. **13-02**

(52) U.S. Cl.

USPC **D13/108**; D3/294

(58) Field of Classification Search

USPC D13/103, 107, 108, 118, 119, 199; D3/273, 274, 294, 295, 302; D14/223

CPC .. H02J 7/0044; H02J 7/0069; A45C 2011/001

(57) **CLAIM**

The ornamental design for a charging case for earphones, as shown and described.

DESCRIPTION

FIG. 1 is a perspective view of a charging case for earphones, showing my new design;

FIG. 2 is a perspective view thereof, showing the design in an open status;

FIG. 3 is a perspective view of the charging case for earphones, shown closed;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines depict portions of the charging case for earphones and form no part of the claimed design.

1 Claim, 9 Drawing Sheets
